UNITED STATES PATENT OFFICE.

JOHN SCHAEFER, OF CHICAGO, ILLINOIS, ASSIGNOR OF ONE-HALF TO WILLIAM STEELE, OF CHICAGO, ILLINOIS.

ENGINE STARTER.

Application filed January 30, 1922. Serial No. 532,540.

To all whom it may concern:

Be it known that I, JOHN SCHAEFER, a citizen of the United States, residing at Chicago, in the county of Cook and State of Illinois, have invented a certain new and useful Improvement in Engine Starters, of which the following is a specification.

This invention relates to that type of manually operated starting mechanisms for explosion engines of automobiles and the like, in which a hand crank has clutch connection with the engine shaft in an automatically detachable manner, and the present improvement has for its object:—

15 To provide a simple and efficient structural assembly of parts whereby an effective cranking of the engine shaft is attained, with an avoidance of injury to the operator when a back kick of the engine takes place, 20 as well as when the engine starts in the proper direction, all as will hereinafter more fully appear.

In the accompanying drawing:—

Fig. 1, is a side elevation of an engine 25 starter mechanism embodying the present invention.

Fig. 2, is a longitudinal section, illustrating one position of the clutching means in full lines in one position and in the other 30 position in dotted lines.

Figs. 3 and 4 are companion transverse sections on line 3,—3, Fig. 2, showing the two positions of the clutch mechanism.

Like reference numerals indicate like 35 parts in the different views.

Referring to the drawing, I designates the forward end of an engine shaft provided with a transverse clutch member or pin 2 as usual.

40 3 designates a fixed journal hub or bracket secured to the forward portion of the vehicle frame with its journal bore in longitudinal alignment with the engine shaft 1 aforesaid.

45 4 designates a tubular outer shaft arranged in the journal hub 3 in a manner permitting rotary movement as well as limited longitudinal adjustment of the shaft in the operation of the mechanism.

50 5 designates an operating hand crank or other usual means fixedly secured to the forward end of the shaft 4 aforesaid.

6 designates a central shaft arranged in the bore of the hollow shaft 5 and provided 55 at its forward end with a head 7 or like

means by which the shaft 6 may be manually rotated when desired. At its rear end the shaft 6 carries a fixed head 8 the rear face of which is formed with triangular projections 8' adapted for positive operative 60 engagement in one direction with the cross pin 2 of the engine shaft, as usual in the present class of starting mechanisms.

9 designates a clutch control collar slid- 65 ingly mounted on the hollow shaft 4 by means of a fixed stud 10 on the shaft 4 and a longitudinal recess 11 in the collar 9, with the fit between said parts of a loose form to permit limited independent turning move- 70 ment of the clutch collar. At its rear end 75 the clutch collar 9 is formed with one or more cam projections 12, the inclines of which are arranged in a direction opposite to the inclines of the cam projections 8' above described. The cam projections 12 75 have operative engagement with correspond- 80 ing cam recesses 13 in the aforesaid head 8, so that when the head 8 receives ro- 85 tative movement in a backward or reverse direction, such cam formation will act to move the clutch collar 9 to attain a release of the hereinafter described clutch means be- 90 tween the shafts 4 and 6.

14 designates one or more pits or recesses formed in the periphery of the central shaft 85 6 aforesaid, and preferably of the semi- spherical form shown.

15 designates one or more radial orifices or passages formed in the outer shaft 4 aforesaid, in line with the pits or recesses 90 14 and adapted to contain members or balls 16 constituting the movable clutch elements between the shafts 4 and 6 in the present improvement.

17 designates a circular groove or channel 95 formed in the inner surface of the clutch collar 9. Said groove in one position of said clutch collar, as shown in full lines in Fig. 2, is out of line with the pits 14 and orifices 15 and the inner surface of the collar 9 is 100 adapted to positively hold the balls 16 in the pits 14 and attain a positive driving connection between the shafts 4 and 6 aforesaid. In the other position of the clutch collar, shown in dotted lines in Fig. 2, the groove 105 17 is in line with the pits 14 and orifices 15 so that the balls 16 are free to move out of the described engagement in the pits 14 and release the positive engagement between the shafts 4 and 6 just described.

18 designates a spring, preferably of the coiled form shown, encircling the tubular shaft 4, and interposed between the adjacent ends of the journal hub 3 and clutch collar 9 with a tendency to yieldingly force the cam projections 12 of said collar to engagement with cam recesses 13 of the head 8 aforesaid.

19 designates a yielding friction head carried by a flexible arm 19' attached to the journal hub 3 and adapted to have frictional bearing against the clutch collar 9 to hold the same against free rotation with the tubular shaft 4 upon which it is mounted. 15 Such frictional retardance of the clutch collar can be increased by grooves 20 formed in the periphery of the clutch collar 9 into which the bearing point of the friction head 19 has engagement requiring an outward 20 displacement of the friction head in a turning movement of the clutch sleeve.

21 designates a spring impelled dog or pawl mounted in the journal hub 3 and adapted for yielding engagement in a peripheral groove 22 in the shaft 4 to hold the same and associated parts in a forward position free from engagement with the engine shaft.

The operation of the mechanism is as follows:—

When a cranking of the engine is required, the positively connected shafts 4, 6 and accessories are manually pushed in a rearward direction from the holding engagement of the dog 21 above described, and so that the cam projection 8' of the head 8 are brought into operative engagement with the cross pin 2 of the engine shaft, so that the desired manual rotation of the engine shaft can be effected and until the normal power rotation of said engine shaft commences. With the commencement of the power rotation of the engine shaft, its cross pin 2 rides against the inclined portions of the cam projections 8' forcing the manual actuating mechanism in a forward direction to be engaged and held by the spring dog 21 in its forward and in active position.

50 In case of a dangerous reverse movement of the parts due to a "back kick" of the engine during the cranking operation a safety release of the outer shaft 4 with its crank handle 5 from the central shaft 6 is automatically effected by an operation of the parts as follows:—

In such reverse movement the cam recesses 13 of the head 8 moving against the cam projections 12 of the frictionally retarded clutch collar 9 imparts an independent forward movement to said clutch sleeve bringing its circular channel 17 in line with the orifices 15 of the outer shaft 4 and the balls 16 confined thereon, and so that said 65 balls are free to move outward into said

channel 17 and out of the normal clutching or holding engagement in the pits 14 of the inner shaft 6, thus releasing the normally existing operating connection between the inner and outer shafts 4 and 6.

Having thus fully described my invention what I claim as new and desire to secure by Letters Patent, is:—

1. An engine starting mechanism, comprising a tubular shaft carrying a manual actuating means, a central shaft arranged in said tubular shaft and having an end formed for operative engagement in one direction with an engine shaft, a journal bearing supporting the shafts in a rotary and longitudinally adjustable manner, a clutch collar slidably mounted on the tubular shaft and formed in its interior with an annular channel, the inner ends of the clutch collar and central shaft having coacting cam formations adapted to impart longitudinal movement to the clutch collar in a reverse rotation of the central shaft, the tubular shaft having a radial opening in its wall, the central shaft having a peripheral recess in line with said opening, and a clutch member movable in said opening and adapted in one position of the clutch collar to be held in positive engagement with the recess in the central shaft and in the other position of the clutch collar to move into the annular channel of said collar and out of positive engagement in said recess. 75 80 85 90 95

2. An engine starting mechanism, comprising a tubular shaft carrying a manual actuating means, a central shaft arranged in said tubular shaft and having an end formed for operative engagement in one direction with an engine shaft, a journal bearing supporting the shafts in a rotary and longitudinally adjustable manner, a clutch collar slidably mounted on the tubular shaft and formed in its interior with an annular channel, the inner ends of the clutch collar and central shaft having coacting cam formations adapted to impart longitudinal movement to the clutch collar in a reverse rotation of the central shaft, the tubular shaft having a radial opening in its wall, the central shaft having a spherical recess in its periphery in line with said opening, and a ball movable in said opening and adapted in one position of the clutch collar to be held in positive engagement with the recess in the central shaft and in the other position of the clutch collar to move into the annular channel of said collar and out of positive engagement in said recess. 100 105 110 115 120

3. An engine starting mechanism, comprising a tubular shaft carrying a manual actuating means, a central shaft arranged in said tubular shaft and having an end formed for operative engagement in one direction with an engine shaft, a journal bearing supporting the shafts in a rotary and 125 130

longitudinally adjustable manner, a clutch 5 collar slidingly mounted on the tubular shaft and formed in its interior with an annular channel, the inner ends of the clutch collar and central shaft having coacting cam formations adapted to impart longitudinal movement to the clutch collar in a reverse rotation of the central shaft, the tubular shaft having a radial opening in its wall, 10 the central shaft having a peripheral recess in line with said opening, a clutch member movable in said opening and adapted in one position of the clutch collar to be held in positive engagement with the recess in the 15 central shaft and in the other position of the clutch collar to move into the annular channel of said collar and out of positive engagement in said recess, and means for retarding the turning movement of the 20 clutch collar.

4. An engine starting mechanism, comprising a tubular shaft carrying a manual actuating means, a central shaft arranged in said tubular shaft and having an end 25 formed for operative engagement in one direction with an engine shaft, a journal bear-

ing supporting the shafts in a rotary and longitudinally adjustable manner, a clutch collar slidingly mounted on the tubular shaft and formed in its interior with an annular channel, the inner ends of the clutch collar and central shaft having coacting cam formations adapted to impart longitudinal movement to the clutch collar in a reverse rotation of the central shaft, the tubular 30 shaft having a radial opening in its wall, the central shaft having a peripheral recess in line with said opening, clutch member movable in said opening and adapted in one position of the clutch collar to be held in 35 positive engagement with the recess in the central shaft and in the other position of the clutch collar to move into the annular channel of said collar and out of positive engagement in said recess, a spring tending to force 40 said clutch collar in an inward direction, and a pawl adapted to engage the tubular shaft and hold the parts in their forward 45 position.

Signed at Chicago, Illinois, this 26th day 50 of January, 1922.

JOHN SCHAEFER.
